UNITED STATES PATENT OFFICE.

VICTOR E. EDWARDS AND JEROME R. GEORGE, OF WORCESTER, MASSACHUSETTS,
ASSIGNORS TO MORGAN CONSTRUCTION COMPANY, OF WORCESTER, MASSACHUSETTS, A CORPORATION OF MASSACHUSETTS.

FEEDING MECHANISM FOR GAS-PRODUCERS.

972,172.

Specification of Letters Patent. Patented Oct. 11, 1910.

Application filed September 30, 1904. Serial No. 226,607.

To all whom it may concern:

Be it known that we, VICTOR E. EDWARDS and JEROME R. GEORGE, citizens of the United States, residing at Worcester, in the county 5 of Worcester and Commonwealth of Massachusetts, have invented a new and useful Improvement in the Feeding Mechanism of Gas-Producers, of which the following is a specification, accompanied by drawings, 10 forming a part of the same, in which—

Figure 1 represents a central, vertical, sectional view of the upper part of the gas producer, having a feeding mechanism embodying our invention. Fig. 2 is a side elevation 15 of the top plate and hollow coal supporting shell suspended therefrom, and Fig. 3 is a top view of the coal supporting shell.

Similar reference letters and figures refer to similar parts in the different views.

20 The object of our present invention is to provide a feeding mechanism for supplying coal to the heating chamber of a gas producer, whereby the coal is uniformly and evenly distributed within the heating chamber, and for providing means for protecting 25 the feeding mechanism from the injurious effects of the excessive heat in the gas producing chamber, and it consists in the construction and arrangement of parts as herein- 30 after described and pointed out in the annexed claims.

Referring to the accompanying drawings, 1 denotes the side walls of the gas producer, and 2 the inclosed gas producing chamber.

35 Supported upon the side walls 1 is a top plate or cover 3, having a central opening 4 surrounded by an upturned flange 5. Concentric with the flange 5 is a similar upturned flange 6, the space inclosed between 40 the flanges 5 and 6 forming a water space 7. Mounted upon the top plate 3, is a hopper-shaped coal reservoir 8 having its lower end circular as at 9, and open for the delivery 45 of coal to the chamber 2. The circular open end 9 is inserted within the concentric flange 5 of the top plate and without the circular end 9, is a depending flange 10, which enters the water space 7, thereby water-sealing the lower end of the coal reservoir. The top 50 plate 3 is provided with hollow bosses, preferably three in number, arranged concentrically about the flange 5, said bosses, one of which is shown at 11, projecting upwardly through the water-sealed space 7. The hubs

11 receive the screw threaded pipes 12 which 55 are rigidly held in the hubs 11 by nuts 13, 14, which permit a vertical adjustment of the pipes 12. Rigidly attached to the lower ends of the pipes 12, and suspended therefrom is a cast iron shell 15, circular in plan 60 view and having the equidistant lateral projecting lugs 16, provided with screw threaded holes to receive the screw threaded lower ends of the suspension pipes 12. The upper surface 17 of the shell 15 is a horizontal 65 plane surface, supported concentrically with the circular lower end 9 of the coal reservoir 8 and also concentrically with the gas producing chamber 2.

The diameter of the circular plane surface 70 17 is greater than the delivery opening in the lower end of the coal hopper 8 and the surface 17 is suspended at such a distance below the lower end of the coal reservoir 8 that the mass of coal falling from the delivery 75 opening of the reservoir 8 will be supported upon the plane surface 17 of the shell 15. Journalized in the step-bearing 18 of the shell 15 and in the bearing 19 at the top of the coal reservoir is a rotating shaft 20, carrying at its upper end a worm gear 21 which is engaged to a worm 22 on a rotating shaft 23. Attached to the lower end of the shaft is a blade 24 with its lower edge in contact with the plane surface 17 of the shell 15 80 causing the coal resting upon the shell 15 to be scraped off the circular edge 25 of the shell 15, and to fall by gravity in an annular ridge 26 within the gas producer chamber 2. The lower surface of the shell 15 is prefer- 85 ably concave as shown at 27 and is lined with some refractory material 28 such as asbestos or fire clay. One of the suspension pipes 12 communicates with a water supply pipe 29 through which a current of water is sup- 90 plied to the interior of the shell 15, and one of the remaining pipes 12 is shorter than the feed pipe and serves as an over flow for the water supply to the shell 15, said over 95 flow water falling into the water-sealed space 100 7 in which it is maintained at a constant level by an over flow pipe 30.

The operation of our improved feeding device is as follows: Coal is supplied in the reservoir 8 in the usual and well known manner in feeding devices of this class. The mass of coal which falls through the opening in the lower circular end 9 of the reser-

voir, is supported in a state of rest upon the plane upper surface 17 of the shell 15 spreading in each direction from the delivery opening of the hopper 8 as indicated by the broken lines 31. Rotary motion is then imparted to the shaft 20 and scraping blade 24 by which the coal is scraped from the plane upper surface 17 of the shell 15 and caused to fall over the concentric circular edge 25 into the gas producing chamber 2. During the operation of the producer a current of water is fed through one of the suspension pipes 12 to the shell 15 and into the water sealed space 7 of the top plate 3.

15. What we claim as our invention and desire to secure by Letters Patent is:—

1. A gas producer, having a heating chamber provided with an opening in its top for the admission of coal, a nonrotatable coal receiving surface adjustably suspended beneath said opening, a coal agitator above said coal receiving surface for moving the coal off said surface, and means extending upward from said surface for operating said coal agitator.
2. A gas producer, having a heating chamber provided with an opening in its top for the admission of coal, a nonrotatable coal receiving surface adjustably suspended beneath said opening, a rotatable coal agitator above said coal receiving surface, and a shaft stepped in said coal receiving surface and extending upward therefrom for rotating said agitator.
3. In a gas producer, the combination with a gas producing chamber having a cover provided with an opening for the admission of coal, of a nonrotatable coal receiving surface placed beneath said opening, means for adjustably suspending said coal receiving surface from said cover, and a movable member between said coal receiving surface and said cover for removing the coal from said coal receiving surface.
4. In a gas producer, the combination with a gas producing chamber having a cover provided with an opening for the admission of coal, annular flanges on the top of said cover inclosing a water space around said opening, hollow bosses on the top of said cover projecting through said water space, suspension pipes held by said bosses, a shell attached to the lower ends of said pipes and communicating therewith, a source of water supply connected to one of said pipes and another of said pipes communicating with said water space on the cover.
5. In a gas producer, the combination with a gas producing chamber having a top plate provided with an opening for the admission of coal, of a shell having a coal receiving surface suspended from said top plate and beneath said opening, means for maintaining a water circulation through said shell, a rotatable scraper having its lower edge in

contact with said surface, and means for actuating said scraper.

6. In a gas producer, the combination with a gas producing chamber having a cover provided with an opening for the admission of coal, of a non rotatable coal receiving surface, beneath said opening, and means for adjustably suspending said coal receiving surface from said cover.

7. In a gas producer, the combination with a gas producing chamber, of a top plate having an opening for the admission of coal, a shell adjustably suspended from said top plate and beneath said opening, and means for maintaining a water circulation through said shell.

8. In a gas producer, the combination of a gas producing chamber, a top plate having an opening for the admission of coal to said chamber, a coal reservoir above said opening and supported on said top plate, screw threaded pipes and nuts by which said pipes are adjustably held in said top plate, a shell attached to the lower ends of said pipes, and a water circulatory system embracing said pipes and said shell.

9. A gas producer, having a heating chamber provided with an opening in its top for the admission of coal, a shell suspended in said chamber having a coal receiving surface on its upper side beneath said opening, and means for maintaining a water circulation through said shell.

10. A gas producer, having a heating chamber provided with an opening in its top for the admission of coal, a nonrotatable shell beneath said opening having a receiving surface for the coal admitted through said opening, means for supporting said shell from the top of said chamber, and means for maintaining a water circulation through said supporting means and said shell.

11. A gas producer, having a heating chamber provided with a cover having an opening for the admission of coal, a non-rotatable platform concentric with said heating chamber having a coal receiving surface below said opening, a rotatable coal agitator arranged to agitate the coal upon said surface and thereby deliver it to said chamber, means above said platform for operating said agitator, and means for suspending said platform from said cover, said suspension means also entirely above said platform and connected with said surface at a distance from its center greater than the length of said agitator.

12. A gas producer, having a heating chamber provided with a cover having an opening for the admission of coal, a non-rotatable platform having a coal receiving surface below said opening and of a larger diameter than said opening, a rotatable coal agitator arranged to agitate coal upon said surface and thereby deliver it to said chamber.

ber, means above said platform for operating said agitator, lugs on said platform, and means above said platform for suspending it from said cover connecting with the upper surface of said lugs.

13. A gas producer, having a heating chamber provided with an opening in its top for the admission of coal, a nonrotatable shell suspended in said chamber having a 10 coal receiving surface beneath said opening,

means for maintaining a water circulation through said shell, and a coal agitator above said coal receiving surface for moving the coal off said surface.

Dated this 26th day of September 1904. 15
